(57) **CLAIM**

The ornamental design for a double kink fishing hook, as shown and described.

DESCRIPTION

FIG. 1 is a perspective view of a double kink fishing hook having a barb and a shank with an eyelet, shown in broken lines, in which the first kink is adjacent to the front length and/or tip and the second kink is adjacent to the shank.

FIG. 2 is a front view of the double kink fishing hook of FIG. 1.

FIG. 3 is a first side view of the double kink fishing hook of FIG. 1.

FIG. 4 is second, opposite side view of the double kink fishing hook of FIG. 1.

FIG. 5 is a top view of the double kink fishing hook of FIG. 1; and,

FIG. 6 is a bottom view of the double kink fishing hook of FIG. 1.

The broken line showing of environment in the drawings is included for the purpose of illustrating only and forms no part of the claimed design.
